THREE-DIMENSIONAL PLASTIC PANEL

Gerald A. Woodman, 2216 Duxbury Circle,
Los Angeles, Calif. 90034

Filed Aug. 22, 1966, Ser. No. 3,556

Term of patent 14 years

(Cl. D13—1)

FIG. 1.

FIG. 2.

FIG. 3.

FIG. 1 is a top plan view of a panel embodying my new design;

FIG. 2 is a bottom plan view thereof; and

FIG. 3 is a sectional view of the panel taken on the line 3—3 shown in FIG. 1.

I claim:

The ornamental design for a three-dimensional plastic panel, as shown and described.
